US00D502100S

(12) **United States Design Patent** (10) Patent No.: **US D502,100 S**
 Bretz et al. (45) Date of Patent: **** Feb. 22, 2005**

(54) **BOTTLE**

(75) Inventors: **John M. Bretz**, Crystal Lake, IL (US); **Susan L. Colten**, Crystal Lake, IL (US); **Rachel Orland**, Chicago, IL (US); **Jeffrey L. Pattee**, Palatine, IL (US); **Susan Vanderwiel**, Palatine, IL (US); **David Piccioli**, Auburn, NH (US); **Bradley L. Allen**, St. Charles, MO (US); **Bryce Rutter**, St. Louis, MO (US); **William Scott Portzline**, Portland, OR (US)

(73) Assignee: **Stokely-Van Camp, Inc.**, Chicago, IL (US)

(**) Term: **14 Years**(21) Appl. No.: **29/180,326**(22) Filed: **Apr. 22, 2003****Related U.S. Application Data**

(63) Continuation of application No. 29/162,343, filed on Jun. 13, 2002, now abandoned, which is a continuation of application No. 29/079,806, filed on Nov. 19, 1997, now abandoned, which is a continuation of application No. 29/064, 097, filed on Dec. 6, 1996, now abandoned.

(51) LOC (7) Cl. **09-01**

(52) U.S. Cl. **D9/500; D9/538**

(58) Field of Search **D9/500-505, 537, D9/538, 539, 540, 549-558, 434; 215/381-384, 370-375**

OTHER PUBLICATIONS

“Snapple” 32 ounce Pet bottle, submitted by applicant in parent application 29/072,878.*

“Gatorade Gripper” bottle, exhibited to public Jun. 29, 1996, submitted by applicant in parent application 29/072,878.*

24 ounce E.D.G.E.(Ergonomic/Worm bottle, exhibited to public Dec. 9, 1996, submitted by applicant in parent application 29/072,878.*

Primary Examiner—Lucy Lieberman

(74) Attorney, Agent, or Firm—Lars S. Johnson; James D. Ryndak

CLAIM

The ornamental design for a bottle, as shown and described.

DESCRIPTION

FIG. 1 is a perspective view of a bottle showing our new design;

FIG. 2 is a front view of the bottle depicted in FIG. 1;

FIG. 3 is a top view of the bottle depicted in FIG. 2;

FIG. 4 is a perspective view of a second embodiment of a bottle depicted in FIG. 1;

FIG. 5 is a front view of the bottle depicted in FIG. 4; and,

FIG. 6 is a top view of the bottle depicted in FIG. 4.

The broken line environmental showing is for illustrative purposes only and does not form part of the claimed design.

1 Claim, 4 Drawing Sheets
